UNITED STATES PATENT OFFICE.

BAZILE MASSÈ, OF ST. HYACINTHE, CANADA, ASSIGNOR TO WILFRID ALFRED MOREAU, OF SAME PLACE.

DISPLAY-STAND.

SPECIFICATION forming part of Letters Patent No. 499,326, dated June 13, 1893.

Application filed May 18, 1891. Renewed February 13, 1893. Serial No. 462,104. (No model.)

To all whom it may concern:

Be it known that I, BAZILE MASSÈ, of St. Hyacinthe, in the Province of Quebec, Canada, have invented a certain new and useful 5 Improved Garment-Holder and Display Stand or Rack; and I do hereby declare that the following is a full, clear, and exact description of the same.

This invention has for its object to produce 10 a piece of furniture especially intended for holding trousers, coats, vests, &c., and the use of which will avoid to a considerable extent the trouble experienced in taking them out of and returning them to the usual drawers 15 in which they are folded and packed and furthermore serve to keep them stretched and in good order more particularly the trousers while allowing the particular pattern of each pair to be seen so that a selection can be made 20 without disturbing the rest. The principle of the holder is embodied in racks formed of rows of spring bars projecting out from a backing or frame of any desired shape and size the same varying with the use to which 25 the holder is to be put, that is to say, if it is to be used by a private individual the arrangement will be small and simple and if it is to be applied in the nature of a display stand in tailoring establishments it will be more 30 extensive and elaborate.

For full comprehension however of the invention, reference must be had to the annexed drawings forming part of this specification, in which like symbols indicate corresponding parts and wherein—

Figure 1 is a perspective view of a holder suitable for use by a private individual; Fig. 2 a similar view of the holder in connection with a stand suitable for a tailoring establishment, a few pairs of trousers being shown in place; Fig. 3 a vertical transverse section of the stand on line x , x , Fig. 2; Fig. 4 a horizontal section of an end portion of the stand on the line z , z , Fig. 2; Fig. 5 a detail cross section of two of the spring bars of the holder and Fig. 6 a view of a rack adapted for holding coats and vests.

Referring to Figs. 1 and 6, A is a plain back board or framing which can be of any desired 50 shape and pattern and be secured to the wall of a cup-board in any way, B B B being pro-

jecting spring bars preferably of the cross section shown in Fig. 5 having a tongue g' on one side and a groove g^2 on the other longitudinally of their length, each with one end set rigidly in the back board and arranged in a horizontal row, the spacing between them preferably varying to suit different thicknesses of garments. The tongue g' and grooves g^2 furnish a better hold upon the garment than if the bars were left plain.

This form of holder will be especially useful for private use while the stand illustrated by the remaining figures is especially intended for store service and it may be described as follows:

C C are two legs or standards; D, D', D', respectively foot and head sections of same and E E' respectively lower and upper central longitudinal bars connecting them. 70 These parts are all secured together in any desired way and a top, or counter portion as it may be termed, which is supported by the head sections D' D' has a level central portion F and two inclined side sections F' F' 75 hinged to such central part so that they can be thrown up and rest against ornamental end pieces f f on top of the stand, the top edges of the head sections being shaped to secure the inclination of the side sections.

G G are the spring bars forming racks on each side of the upper longitudinal bars E' and being set in same as before mentioned such distances apart as will allow of the easy insertion and withdrawal of the garments in 85 the direction of the length of the bars but not sufficient to allow them to be pulled down or up through them, the tongue and groove affording a hold in this respect.

H H are extra longitudinal bars arranged 90 between the foot sections D D so that should it be desired to keep the trousers in a stretched condition nippers h h preferably flexibly connected to such longitudinal bars can be attached to the ends of the garments.

While withdrawing or replacing the garments the hinged sections F' F' of the top or counter are thrown up into the position shown in Figs. 2 and 3, their normal position being down, when they afford additional surface on 100 which several garments can be laid during examination by customers, and further they

act to a considerable extent in preserving the garments from dust, &c., besides presenting a tidy appearance.

What I claim is as follows:

- 5 1. A garment holder and display stand or rack composed of a backing or frame and spring bars in the form of straight fingers set in said backing and projecting therefrom parallel with each having a longitudinal depression and rib on opposite sides and other from end to end and each finger forming with every other, racks for the purpose set forth.
- 10 2. A garment holder and display stand or rack formed of single end legs or standards and transverse sections connected at their bases by one or more longitudinal bars; a single longitudinal bar connecting the upper ends of said legs or standards at points a short distance below the top of same; transverse
- 15 3. A garment holder and display stand or rack formed of end legs or standards connected at their bases by one or more longitudinal bars; a single longitudinal bar connect-
- 20
- 25

ing the upper ends of said legs or standards at points a short distance below the top of same; transverse head sections carried in the upper ends of said standards; a top portion having hinged outer side sections and carried by said head sections; and spring bars set into said single longitudinal bar and forming horizontal racks beneath said top portion for the purposes set forth.

4. A garment holder and display stand or rack formed of end legs or standards with foot sections connected by a central and two side longitudinal bars; a single longitudinal bar connecting the upper ends of said legs or standards at points a short distance below the top of same; transverse head sections carried in the upper ends of said standards; a top portion carried by said head sections; spring bars set into said single longitudinal bar and forming horizontal racks beneath said top portion; and nippers flexibly connected with and carried by said side longitudinal bars for the purposes set forth.

St. Hyacinthe, the 11th day of May, 1891.

BAZILE MASSÈ.
